[57] CLAIM

The ornamental design for fold down foot for a trash can, as shown and described.

DESCRIPTION

FIG. 1 is a perspective view for the first embodiment of a fold down foot for a trash can;

FIG. 2 is an enlarged top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a perspective view for a second embodiment of a fold down foot for a trash can;

FIG. 9 is an enlarged top plan view thereof;

FIG. 10 is a bottom plan view thereof;

FIG. 11 is a front elevational view thereof;

FIG. 12 is a rear elevational view thereof;

FIG. 13 is a right side elevational view thereof; and,

FIG. 14 is a left side elevational view thereof.

The broken line showing of a partially shown trash can in FIGS. 1 and 8 is for illustrative purposes only and forms no part of the claimed design.
